Attorney.

UNITED STATES PATENT OFFICE.

ALBERTO I. WOODRING, OF WATERLOO, IOWA, ASSIGNOR, BY MESNE ASSIGNMENTS,
TO NATIONAL SAFETY DEVICE COMPANY, OF WATERLOO, IOWA.

AUTOMATIC BELL-RINGING DEVICE.

Application filed March 17, 1922. Serial No. 544,643.

To all whom it may concern:

Be it known that I, ALBERTO I. WOODRING, a citizen of the United States of America, and a resident of Waterloo, Blackhawk 5 County, Iowa, have invented certain new and useful Improvements in Automatic Bell-Ringing Devices, of which the following is a specification.

My invention relates to improvements in 10 automatic bell-ringing devices, and the object of my improvement is to supply for a signal-bell or the like, mechanism operatively connected between said signal and a movable controller-element, to automatically 15 actuate the signal when said controller-element is shifted in one direction to start a vehicle, to whose motor-driven mechanism it is operatively connected.

This object I have accomplished by the 20 means which are hereinafter described and claimed, and which are illustrated in the accompanying drawings, in which Fig. 1 is a diagrammatic elevation of my improved apparatus as operatively connected between 25 a bell-signal and a movable controller-element; Fig. 2 is a top plan of the same, with parts removed or broken away; and Fig. 3 is an enlarged central vertical section of a fluid-pressure operating-valve, parts including 30 a cam, a contact-device and an automatic locking-device being shown in elevation, with other elements broken away.

While my invention is particularly appropriate for employment on railway locomotives, or other motor-propelled vehicles, 35 it is obvious that it may be used in connection with any species of signaling-device and with a controller-element, in automatically operating the signaling-device at each 40 power-actuating movement of the controller-element.

The installation illustrated is that specific to a railway locomotive. The numeral 1 denotes a throttle-lever which is swingingly 45 mounted at one end on the throttle-lever fulcrum 56 to be manually swung upon and along the fixed quadrant 2, the latter being provided with the usual teeth on its convex edge to receive the usual-spring controlled 50 detent on a handle pivoted to the lever.

This lever is used when swung in one direction to open the throttle-valve of the locomotive by operative connections.

The numeral 3 denotes a cam-block, having 55 two levels separated by a curved shoulder

4, the part of the lower level having a short longitudinal slot 5 to adjustingly receive a headed screw 6 inserted in a threaded socket in the lever 1, the top of the screw being flush with the top of said level, and the cam 60 being adjustably secured thereby across the lever. Any other desired fastening means may be used instead.

Referring to said Fig. 3, the numeral 18 denotes a fluid-pressure actuated device, 65 whose chamber is fixed upon a bracket-arm 16 about midway between the fulcrum 56 and the quadrant 2. A pair of spaced hangers 14 are secured to the base of this chamber by means of bolts 17, and on a 70 pintle-bolt 13 fixed across these hangers is pivoted one end of a contact-device comprising the swinging arm 12 having on opposite sides of its outer end the abutment shoulders 11, and having a cross-pintle 10 75 on whose ends the upper ends of fingers 9 are pivoted abutting upon the shoulders 11 and stopped by the latter against movement in one direction. A pintle 8 connects the spaced lower ends of the fingers 9 and a 80 roller 7 is rotatably mounted thereon to ride along and upon the cam 3 longitudinally as the latter is moved thereunder by reason of the swinging of the lever 1 to and fro. An adjusting-screw 15 is movable through a 85 threaded opening in a cross-part of the hangers 14 to adjustably act upon the under edge of the arm 12 in keeping it positioned properly to maintain the roller 7 to contact with said cam. 90

The valve-chamber 18 contains two chambers 26 and 22, the one above the other, and placed in occasional communication by means of a valve-port 24 in which is seated slidably the channeled guide-part 25 of a solid 95 valve-head which is normally kept closed by the yielding pressure of a coiled spring 29 in said chamber 26. The base of the chamber 18 has an opening in which is seated the threaded adjustable plug 20, centrally oriented to seat the reciprocable rod 19, the lower end of the latter riding upon the upper edge of the arm 12, and a boss on the valve 25 being alined with and contacting with the upper end of this rod. 100

An angular passage 32 in the wall of said chamber 18 communicates between the chamber 22 and a seat 33 for a ball check-valve, said seat communicating with one end of a pipe 31 leading to the bell-motor 52, which 110

actuates the rod 53 and crank 54 of the bell 55. A pipe 35 leads from the reservoir 48 to a passage 27 in the wall of the valve-chamber 18, and the passage 27 is in communication with the chamber 26. A cross-connection between a T-coupling 49 in the pipe 35 and the other pipe 31 includes a chamber 50 with stop-cock valve which may be operated manually by means of a crank-handle 51 when desired to ring the bell 55 independently of said ringing device.

The numeral 42 denotes an integral bracket projecting first horizontally and then downwardly from the upper part of the valve-chamber 18. In the depending part of said bracket is mounted an adjustable screw 44 with nut 43, and on the inner end of the screw is mounted a short helical spring 41. The numeral 47 denotes a locking-arm whose upper end is positioned within a longitudinal slot 45 in said bracket and pivotally hung on a pintle 46. The chamber 18 has a horizontal cylindric opening 36 leading into the upper chamber 26, the outer end closed by a stuffing-box or threaded plug 39 orificed to slidably seat a plunger-rod 40 whose outer end engages the adjacent edge of the arm 47. On the inner end of the plunger-rod is secured a cupped leather part 37 serving to make a tight joint with said opening 36, and held by a nut 38. The arm 47 is positioned above the arm 12 with its lower end in contact therewith when the air-pressure in the chamber 26 is below a determined minimum amount, to stop or prevent movement of the arm 12 upwardly, when the arm 12 is in its lowered position in engagement with the shoulder 4 of the cam 3 and indicated by the dotted lines in said Fig. 3.

When the air-pressure in said chamber 26 is above said determined minimum, the plunger-rod 40 is pushed outwardly to swing the arm 47 outwardly enough to clear the arm 12, compressing said spring 41, which reacts when the pressure falls below said limit to return the arm 47 to its locking position.

When the engineer swings the throttle-lever (or the controller-arm of the controller of the electric or other motor of a motor-car) in a direction to open the throttle, (or turn on the power-supply of such car), the lower part of the cam 3 passes under the roller 7 of said contact-device without actuating the latter until said roller is lifted yieldingly in passing the shoulder 4 to be seated upon the higher level of the cam. This lifts the rod 19, and the valve 25, compressing the spring 29, permitting compressed air to pass from the chamber 26 into the chamber 22, and thence past the check-valve to the pipe 31 to operate the bell-motor 52. When the throttle-lever 1 in moving forward removes the cam 3 from under the contact-device, the

latter drops down, the spring 29 presses down the valve 25 to close it, and the bell stops ringing as soon as its momentum of inertia ceases. When the lever 1 is returned to its first position, the abrupt end of the cam 3 swings the arms 9 upwardly, without operating the contact-arm 12. It should be noted that because of the unavoidable lost motion in the operative connections to the throttle-lever, the cam 3 will begin operating the bell-signal a short time before the throttle is opened to start the locomotive.

As the purpose of this device is that of a safety-device to warn persons that the locomotive is about to start, this preliminary ringing of the bell is effectual in giving the alarm before any person can be injured as a result of such starting.

It is to be also observed, that as the above described locking-device functions automatically to lock the contact-device upon the cam 3, that the throttle-lever cannot be moved to start the locomotive, until the engineer causes the air-pressure to be pumped up to the required amount to disengage the locking-arm 47. The locomotive cannot be started until this is done, unless in some unusual emergency or otherwise the engineer finds it useful to block the arm 47 to keep it from locking the contact-device.

Having described my invention, what I claim as new and desire to secure by Letters Patent, is:

1. In combination, a movable controller-element, a movable contact-device having a finger-part mounted movably thereon the movement of said finger in one direction being limited thereby, said controller-element being movable to and fro past said finger-part to operate it only while passing it in one direction to cause it to change the position of said contact-device, a signaling-device, fluid-actuated mechanism between said contact-device and said signaling-device for operating the signaling-device, and a catch normally engaging and holding said contact-device and operated by said mechanism to release the contact-device only when the mechanism is acted upon by a fluid at or above a determined pressure.

2. In combination, a movable controller-element, a movable contact-device having a finger-part mounted movably thereon the movement of said finger in one direction being limited thereby, said controller-element being movable to and fro past said finger-part to operate it only while passing it in one direction to cause it to change the position of said contact-device, a signaling-device, operative connections between said contact-device and said signaling-device, and a releasable catch locking said contact-device in one position.

3. In combination, a signaling-device, a movable contact-device, operating means

separably entrained with said contact-device and with said signaling-device including a fluid pressure motor having a valve to operate the signaling device only when the contact-device is moved in one direction, and a resiliently controlled catch independently associated with said operating-means to be moved by said fluid element only when the latter is at or above a determined pressure 5 to be held out of locking association with said operating means, or to be reactively returned to engage an element of said operating means causing said element to rigidly interlock with said contact-device, when the 10 fluid is below said determined pressure.

4. In combination, a movable controller-element having a cam fixed thereon, a movable contact-device having a finger-part pivotally mounted for limited movement in one direction, said controller-element while moving in one direction only engaging said cam with said finger-part to cause the latter to change the position of said contact-device, a source of fluid under pressure, a bell-signal, a motor operatively connected to said bell-signal and operable by a fluid under pressure, a valve-chamber having separated receiving and delivery chambers in communication with both said source of fluid 20 under pressure and with said motor respectively, a resiliently-controlled valve adapted to control the passage of said fluid between the chambers, a plunger mounted in said receiving chamber, projecting therefrom into contact with said contact-device and movable by the latter to open said valve, a swingingly-mounted arm, a plunger reciprocably mounted in the chamber of said valve which contains fluid under constant pressure and projecting therefrom to engage said arm to thrust it in one direction out of engagement 25 with said locking-device while said fluid is over a determined pressure, and adjustable tensioning-means, operable upon said arm to yieldingly propel it in a direction to engage and rigidly hold said contact-device in 30 interlocked engagement with said controller-element when the fluid in said valve-chamber is below said determined pressure.

35 5. In combination, a movable controller-element having a cam fixed thereon, a movable contact-device having a finger-part pivotally mounted thereon for limited movement in one direction, means for adjusting the extent of movement of said contact-device, said controller-element while moving 40 in one direction only engaging said cam with said finger-part to cause the latter to change the position of said contact-device, a source of fluid under pressure, a bell-signal, a motor operatively connected to said bell-signal and operable by a fluid under pressure, a valve-chamber having separated receiving and delivery chambers in communication with both 45 said source of fluid under pressure and with said motor respectively, a resiliently-controlled valve adapted to control the passage of said fluid between the chambers, and a plunger mounted in said receiving chamber, projecting therefrom into contact with said contact-device and movable by the latter to 50 open said valve.

55 6. In combination, a movable controller-element having a cam fixed thereon, a movable contact-device having a finger-part pivotally mounted thereon for limited movement in one direction only engaging said cam with said finger-part to cause the latter to change the position of said contact-device, a source of fluid under pressure, a bell-signal, a motor operatively connected to said bell-signal and operable by a fluid under pressure, a valve-chamber having separated receiving and delivery chambers in communication with both said source of fluid under pressure and with said motor respectively, a resiliently-controlled valve adapted to control the passage of said fluid between the chambers, and a plunger mounted in said receiving chamber, projecting therefrom into contact with said contact-device and movable by the latter to 60 open said valve.

65 7. In combination, a movable controller-element having a cam fixed thereon, a movable contact-device having a finger-part pivotally mounted thereon for limited movement in one direction only engaging said cam with said finger-part to cause the latter to change the position of said contact-device, a source of fluid under pressure, a bell-signal, a motor operatively connected to said bell-signal and operable by a fluid under pressure, a valve-chamber having separated receiving and delivery chambers in communication with both said source of fluid under pressure and with said motor respectively, a resiliently-controlled valve adapted to control the passage of said fluid between the chambers, and a plunger mounted in said receiving chamber, projecting therefrom into contact with said contact-device and movable by the latter to 70 open said valve.

75 8. In combination, a movable controller-element having a cam fixed thereon, a movable contact-device having a finger-part pivotally mounted thereon for limited movement in one direction only engaging said cam with said finger-part to cause the latter to change the position of said contact-device, a source of fluid under pressure, a bell-signal, a motor operatively connected to said bell-signal and operable by a fluid under pressure, a valve-chamber having separated receiving and delivery chambers in communication with both said source of fluid under pressure and with said motor respectively, a resiliently-controlled valve adapted to control the passage of said fluid between the chambers, and a plunger mounted in said receiving chamber, projecting therefrom into contact with said contact-device and movable by the latter to 80 open said valve.

85 9. In combination, a movable controller-element having a cam fixed thereon, a movable contact-device having a finger-part pivotally mounted thereon for limited movement in one direction, means for adjusting the extent of movement of said contact-device, said controller-element while moving 90 in one direction only engaging said cam with said finger-part to cause the latter to change the position of said contact-device, a source of fluid under pressure, a bell-signal, a motor operatively connected to said bell-signal and operable by a fluid under pressure, a valve-chamber having separated receiving and delivery chambers in communication with both said source of fluid under pressure and with said motor respectively, a resiliently-controlled valve adapted to control the passage of said fluid between the chambers, and a plunger mounted in said receiving chamber, projecting therefrom into contact with said contact-device and movable by the latter to 95 open said valve.

100 10. In combination, a movable controller-element having a cam fixed thereon, a movable contact-device having a finger-part pivotally mounted thereon for limited movement in one direction, means for adjusting the extent of movement of said contact-device, said controller-element while moving 105 in one direction only engaging said cam with said finger-part to cause the latter to change the position of said contact-device, a source of fluid under pressure, a bell-signal, a motor operatively connected to said bell-signal and operable by a fluid under pressure, a valve-chamber having separated receiving and delivery chambers in communication with both said source of fluid under pressure and with said motor respectively, a resiliently-controlled valve adapted to control the passage of said fluid between the chambers, and a plunger mounted in said receiving chamber, projecting therefrom into contact with said contact-device and movable by the latter to 110 open said valve.

115 11. In combination, a movable controller-element having a cam fixed thereon, a movable contact-device having a finger-part pivotally mounted thereon for limited movement in one direction, means for adjusting the extent of movement of said contact-device, said controller-element while moving 115 in one direction only engaging said cam with said finger-part to cause the latter to change the position of said contact-device, a source of fluid under pressure, a bell-signal, a motor operatively connected to said bell-signal and operable by a fluid under pressure, a valve-chamber having separated receiving and delivery chambers in communication with both said source of fluid under pressure and with said motor respectively, a resiliently-controlled valve adapted to control the passage of said fluid between the chambers, and a plunger mounted in said receiving chamber, projecting therefrom into contact with said contact-device and movable by the latter to 120 open said valve.

120 12. In combination, a movable controller-element having a cam fixed thereon, a movable contact-device having a finger-part pivotally mounted thereon for limited movement in one direction, means for adjusting the extent of movement of said contact-device, said controller-element while moving 120 in one direction only engaging said cam with said finger-part to cause the latter to change the position of said contact-device, a source of fluid under pressure, a bell-signal, a motor operatively connected to said bell-signal and operable by a fluid under pressure, a valve-chamber having separated receiving and delivery chambers in communication with both said source of fluid under pressure and with said motor respectively, a resiliently-controlled valve adapted to control the passage of said fluid between the chambers, and a plunger mounted in said receiving chamber, projecting therefrom into contact with said contact-device and movable by the latter to 125 open said valve.

125 13. In combination, a movable controller-element having a cam fixed thereon, a movable contact-device having a finger-part pivotally mounted thereon for limited movement in one direction, means for adjusting the extent of movement of said contact-device, said controller-element while moving 130 in one direction only engaging said cam with said finger-part to cause the latter to change the position of said contact-device, a source of fluid under pressure, a bell-signal, a motor operatively connected to said bell-signal and operable by a fluid under pressure, a valve-chamber having separated receiving and delivery chambers in communication with both said source of fluid under pressure and with said motor respectively, a resiliently-controlled valve adapted to control the passage of said fluid between the chambers, and a plunger mounted in said receiving chamber, projecting therefrom into contact with said contact-device and movable by the latter to open said valve.

and rigidly hold said contact-device in interlocked engagement with said controller-element when the fluid in said valve-chamber is below said determined pressure, and a 5 manually-controllable valve positioned in and adapted to control the communication between said bell-motor and said delivery-chamber of said valve.

8. In combination, a movable controller-10 element having a cam adjustably fixed thereon, a movable contact-device having a finger-part pivotally mounted thereon for limited movement in one direction, said controller-element while moving in one direction only 15 engaging said cam with said finger-part to cause the latter to change the position of said contact-device, a source of fluid under pressure, a bell-signal, a motor operatively connected to said bell-signal and operable by 20 a fluid under pressure, a valve-chamber having separated receiving and delivery chambers in communication with both said source of fluid under pressure and with said motor, respectively, a resiliently-controlled valve 25 adapted to control the passage of said fluid between the chambers, and a plunger mounted in said receiving chamber, projecting therefrom into contact with said contact-device and movable by the latter to open said 30 valve.

9. In combination, a starting-element for initiating actuation in a driven element, a signaling-device, a motor for operating said signaling-device in communication with a 35 supply of fluid under pressure, a valve-chamber in said communication containing a valve yieldingly closing the communication, and means for moving said valve to

open said communication including a contact-element positioned for occasional operative engagement with said starting-element only while the latter is in a primary stage of movement in one direction to open the valve and begin to operate said motor and signaling-device before the starting-element has initiated an actuation of said driven element.

10. In combination, a starting-element for initiating actuation in a driven element, a signaling-device, a motor for operating said signaling-device in communication with a supply of fluid under pressure, a valve-chamber in said communication containing a valve yieldingly closing the communication, and means for moving said valve to 50 open said communication including a contact-element positioned for occasional operative engagement with said starting-element only while the latter is in a primary stage of movement in one direction to open the valve and begin to operate said motor and signaling-device before the starting-element has initiated an actuation of said driven element, a movable device normally holding said contact-element in engagement with 55 said starting-element to prevent operation of the latter, and a motor in communication with and adapted to be actuated by said fluid supply only when the fluid is at or above a determined pressure to then operate said 60 movable device to disengage it from said starting-device.

Signed at Waterloo, Iowa, this 13th day of March, 1922.

ALBERTO I. WOODRING.
